ADVERTISING NOVELTY

Fredrick A. Moore, Great Bend, Kans.

Application April 17, 1936, Serial No. 74,879
Renewed November 1, 1937

1 Claim. (Cl. 40—1)

This invention relates to an advertising novelty. The object of my invention is to provide a device of the kind mentioned which has value as a utility as well as advertising qualities. A further object is to provide a means of suspending a book, such as a telephone directory, a catalogue or similar book, on a desk or table or the like in a convenient place. A still further object is to suspend the book on an element that is extensible so that the book may be moved to convenient positions or places for use. Another object is to provide a device of the kind mentioned in which an advertising token is employed as a counterbalance element for the book. A still further object is to provide a device of the kind mentioned in which the advertising token is associated with the book in such close relation that a person's attention will be immediately attracted to the advertising token when that person takes hold of the book or the element supporting the book when the person goes to use the book. These and other objects will be made more apparent as this description progresses.

Now referring to the drawing; Fig. 1 is an elevation of a corner of a table or desk to which my advertising novelty has been applied. Fig. 2 is a sectional view taken along the line II—II and looking in the direction of the arrows. Fig. 3 is an elevation of the corner of a table or desk to which a modified form of the invention has been applied. Similar numerals of reference designate the same part throughout the several figures of the drawing.

In the drawing is shown a desk or table having a top 10 that is supported by the leg 11. The top 10 extends beyond the leg as illustrated at 10x. At 12 is a rubber vacuum or suction cup element that is attached to the under side of the projection of the desk top 10. The cup 12 is provided with a ring 13 through which is passed a string or other flexible element 14. At 15 is shown a book such as a telephone directory, a catalogue or the like. At 16 is an advertising token that is suspended on one end of the string 14 and the book 15 is suspended on the other end of the string 14. At 17 is a ring through which passes both ends of the string 14, the object of which will be later explained.

In the drawing the advertising token is shown as being a representation of a gasoline pump which would be appropriate for advertising for some oil company. It is obvious that the token might be a representation of a tire to advertise some tire company or the token might represent a loaf of bread to advertise some bakery, etc.

Referring to Fig. 3, the element 14 is supported by a screw eye 12x which is screwed into the under side of the top 10. It is obvious that in taking hold of the book 15 or the element 14 to raise the book to a position where it may be used that the token 16 will also be raised and will dangle from the ring 17 and will attract attention to the token whereupon it has served its purpose 15

It is also obvious that the element 14 may be slipped through the ring 13 so that the book may be moved substantially the full length of the cord 14 and when the book is dropped to the floor, the token will act as a counterbalance to raise the book from the floor and take up any slack that there might be in the cord 14.

Such modifications of my invention may be employed as lie within the scope of the appended 25 claim without departing from the spirit and intention of my invention. Now having fully explained my invention, what I claim as new and desire to secure by Letters Patent is:—

In an advertising device of the class described; 30 a suction cup having an apertured element thereon, said suction cup being adapted to be attached to a supporting object, a flexible element, said flexible element being slidably supported by said apertured element, a book and an advertising object, said book being supported on one end of said flexible element and said advertising object being supported on the other end of said flexible element as a counterbalance for said book; means for attracting attention to said advertising object, said means comprising a ring that is 35 positioned around the end portions of said flexible element in such a manner that when the book is picked up the advertising object will dangle approximately therefrom as and for the 40 purpose specified. 45

FREDRICK A. MOORE.
